ADJUSTABLE LINEAR CAM DRIVE

Glade M. Stockwell, Cedar Rapids, Iowa, assignor to Collins Radio Company, Cedar Rapids, Iowa, a corporation of Iowa

Filed Aug. 13, 1958, Ser. No. 754,874

2 Claims. (Cl. 74—55)

This invention relates to an adjustable linear cam drive wherein the total movement of the follower can be adjusted without changing the cam shape, size, or its angular displacement and yet maintain linearity of travel.

Previous to this invention difficulty was experienced in matching electrical components with mechanical linear cam drives so that a desired mechanical rotation of the cam gave a required electrical performance. There are various methods that have been known prior to this invention which the manufacturer can follow to match the rise of the cam with the electrical component, namely: (1) the cam can be modified to match the electrical performance of the component, (2) the dial or other controlling means can be calibrated individually for each electrical component, (3) an arbitrary scale can be correlated with the actual electrical performance by tabulated means, (4) the angular displacement of the cam may be modified to meet the requirements of the electrical component, or (5) the electrical component can be adjusted to conform with the mechanical drive. The latter method is generally used to match the two components; however, all of these methods are expensive and difficult to perform.

It is an object of this invention to provide a cam drive where the total movement of the follower can be adjusted and yet maintain linearity of the movement so that the indicator or dial or other controlling means need not be changed or hand-calibrated to conform to the electrical components.

It is a further object of this invention to provide an adjustable cam follower which will permit an easy mechanical adjustment to provide for the variations in electrical characteristics of the components without necessitating recalibration of the mechanical scale or modification of the cam or cam drive.

Further objects, features, and advantages of this invention will become apparent from the following description and claims when read in view of the accompanying drawings, in which:

Figure 1 is a perspective view of one embodiment of the invention, and

Figure 2 illustrates a mathematical description of the operation of the invention.

With reference to Figure 1, an adjustable linear cam drive is supported by a frame or chassis 10. A slug-tuned coil 11 of a well-known type is mounted on chassis 10 by a C type bracket 12. Bracket 12 includes C members 13 surrounding the coil, and formed with a base 14 secured to the chassis by screws 15. A tubular core 16 of the coil permits the insertion of a tuning slug 17 axially supported at one end by a shaft 18.

A supporting member 19 threadedly receives the opposite end of shaft 18. Accordingly, movement of supporting member 19 moves the slug in or out of the tubular core, thus changing the inductance of the coil.

Supporting member 19 has a portion 20 slideably mounted in square slides 21 and 22 attached to the chassis by means of screws 42. Dowel pins 23 and 24 are

2

mounted in the central portions of the respective slides 21 and 22 and extend through a pair of slots 25 and 26 in portion 20 which supports member 19.

A spring 43 between dowel pin 23 and the end of slot 25 biases a cam follower surface 35 against a cam 39. The spring is retained against dowel pin 23 by means of retaining pin 44 and is retained in the end of slot 25 by a hole, not shown, longitudinally placed into the supporting member. The slides and pins confine the movement of supporting member 19 along the axis of the coil.

Another portion 27 of the supporting member 19 supports a cam follower sector 28, a follower arm pivot 29, a follower arm locking assembly 30, 31, 32 and a scale indicator 34. Follower sector 28 has a hole 45 at its center of curvature which receives a dowel pin 29 attached to the supporting portion 27. A follower surface 35 of sector 28 is flat and smooth. An arcuate scale part 33 of follower sector 28 contains graduations which will be discussed in a subsequent section. An indicator 34 is attached to supporting member 19 and cooperates with the scale.

A locking assembly 36 comprises a stud 32 attached to supporting portion 27 and a washer 30 and nut 31. They are tightened to prevent rotation of sector 28 about its pivot 29.

A shaft 37 is rotatably mounted in a bearing 38 which is secured in the chassis. An involute cam 39 is fixed on the shaft and is in engagement with and in the same plane as the follower arm. It is secured to the shaft by a set screw 42 transversely screwed through a collar 40 of the cam. A knob 41 is attached to an end of shaft 37.

In operation, the supporting member 19 is slideably moved along the axis of the coil by the action of the involute cam 39 against the flat linear portion 35 of the follower sector 28. The total distance that the slug will move for a given number of degrees rotation will depend on the angular setting of the flat portion 35 of the follower sector. The setting can be changed by loosening the nut 31 and physically rotating the sector about its pivot 29.

The scale 33 in conjunction with indicator 41 can be used as a guide to determine the new or required setting. However, regardless of the angular setting of the follower sector, the movement of the supporting member 19 will always remain linear due to the inherent property of the involute cam acting against a flat surface.

The operation of the involute cam and flat follower can be better explained by referring to Figure 2.

Mathematically, the involute of a circle is developed by unwrapping a string or similar substance from around the circumference of a circle. As it is being unwrapped, the end of the string will transcribe an arc of constantly and uniformly increasing radii. The arc thus formed is an involute curve of a circle. The curve thus developed is used as the cam surface of this invention.

If a cam is constructed with the involute as the engaging surface and is initially rotated through an angle α , it will engage a flat-edged follower which is set at an angle Ad_1O at point A. If the cam is then further rotated through an angle θ , A' will engage the follower, moving it back along the center point axis to A''. The distance that the follower is forced back is proportional to the increase in cam radius A'O, which is also proportional to the tangent A'B'. Thus if the tangents AB, A'B' etc. increase linearly with equal degrees rotation, the cam radii will also increase linearly in like manner. It can also be seen that A'B' increased in length over AB by the arcuate portion of the circumference BB'. This portion represents the portion of the circumference that would be subtended by every angular rotation equal to the angle θ .

Therefore each tangent for every rotation θ increases the same amount.

The follower must be flat since it is confined to a

direction of motion at angles to the contact point axis. Thus as the follower moves along the line Od_2 , the cam rotating in a counterclockwise direction, must contact the follower at higher and higher points as it moves through subsequent angles of θ . In the design of involute surfaces operating on involute gear teeth or straight-edge follower surfaces, a change in effective pitch radius between an involute cam and its mating surface produces a corresponding change in the distance the mating surface will travel. If the pitch radius is increased the mating surface will increase its travel by a corresponding amount. An increase or decrease in the angle of the follower of this invention will produce a corresponding increase or decrease in the pitch radius.

Since the radius of a straight follower is infinite, the "line of centers" will be perpendicular to the movement of the follower and through the center of the base diameter circle of the involute cam. With a follower angle ϕ_1 , the "line of centers" (Figure 2) will intersect the tangent line AB at point P. The distance PO is defined as the pitch radius (R). If the follower angle is changed to ϕ_2 the tangent A'B' intersects the "line of centers" at P'. Thus it can be obviously seen that the pitch radius has been increased by increasing the angle of the contact point axis from ϕ_1 to ϕ_2 .

The above can be illustrated mathematically as follows: If D_b is the base circle diameter of the involute cam then

$$D_b = 2R \cos \phi_1$$

or

$$R = \frac{D_b}{(2) \cos \phi_1} \quad (1)$$

Further if S is the total movement of the cam follower with 360° rotation of the cam, and α is the number of degrees of actual rotation of the cam then

$$S_1 = \left[\frac{2\pi R}{(2) \cos \phi_1} \right] \frac{\alpha}{360^\circ} \quad (2)$$

Substituting Equation 1 in 2

$$S_1 = \left[\frac{\pi D_b}{\cos \phi_1} \right] \frac{\alpha}{360^\circ}$$

With any given values of D_b and α where S_2 is the new distance of movement of follower arm with $\cos \phi_2$

$$\frac{S_2}{S_1} = \frac{\cos \phi_1}{\cos \phi_2}$$

or

$$S_2 = \frac{S_1 \cos \phi_1}{\cos \phi_2} \quad (3)$$

From Equation 3 the maximum movement of the fol-

lower arm can be calculated, or if the distance is known, the follower angle ϕ can be calculated. The cam and follower are very adaptable where a scale has already been engraved or printed, or a mechanical drive with a fixed angular displacement has been designed, but it subsequently becomes necessary to move the tuning element or slug a total distance slightly more or less than the original setting in order to allow the production electrical deviations in each individual tuning member to conform mechanically to the scale or drive mechanism. Since any change in the angular setting of the follower sector will always maintain a linear movement there is no necessity of either constructing a new scale or drive on performing adjustments to other components in the circuit. This invention then allows a simple mechanical adjustment to displace the time-consuming practice of redesigning or trimming coils or adjusting other elements in order that they will conform to the exerting scale or drive mechanism.

Although this invention has been described with respect to a particular embodiment thereof, it is not to be so limited as changes and modifications may be made therein which are within the full intended scope of the invention as defined by the appended claims.

25 I claim:

1. An adjustable linear cam drive comprising a mounting means, an involute cam rotatably mounted on said mounting means, a supporting member slideably mounted on said mounting means, a flat cam follower adjustably mounted on said supporting means, said flat portion engaging said involute surface of said involute cam, and a means for permitting adjustment of the flat cam follower with respect to the direction of movement of said slideably mounted supporting means including a pivot permitting rotatable adjustment of said follower sector and a locking means for securing said adjustment.

2. An adjustable linear cam drive as claimed in claim 1 characterized in that the flat follower arm includes an indicating means for accurately setting the total travel of said supporting means.
